CLAIM

I claim the ornamental design for a food carton cover panel.

DESCRIPTION

FIG. 1 is a top perspective view of a cover panel of a box blank showing my new design, the broken line showing of the adjacent appended components is for illustrative purposes only and forms no part of the claimed design;

FIG. 2 is a top plan view of the cover panel;

FIG. 3 is a bottom plan view of the cover panel;

FIG. 4 is a front elevation view of the cover panel;

FIG. 5 is a right side elevation view of the cover panel;

FIG. 6 is a left side elevation view of the cover panel;

FIG. 7 is a rear elevation view of the cover panel;

FIG. 8 is a top perspective view of a cover panel of a box blank showing a second embodiment of my new design, the broken line showing of the adjacent appended components is for illustrative purposes only and forms no part of the claimed design;

FIG. 9 is a top plan view of the second embodiment;

FIG. 10 is a bottom plan view of the second embodiment;

FIG. 11 is a front elevation view of the second embodiment;

FIG. 12 is a right side elevation view of the second embodiment;

FIG. 13 is a left side elevation view of the second embodiment;

FIG. 14 is a rear elevation view of the second embodiment;

FIG. 15 is a top perspective view of a cover panel of a box blank showing a third embodiment of my new design, the broken line showing of the adjacent appended components is for illustrative purposes only and forms no part of the claimed design;

FIG. 16 is a top plan view of the third embodiment;

FIG. 17 is a bottom plan view of the third embodiment;

FIG. 18 is a front elevation view of the third embodiment;

FIG. 19 is a right side elevation view of the third embodiment;

FIG. 20 is a left side elevation view of the third embodiment;

FIG. 21 is a rear elevation view of the third embodiment;

FIG. 22 is a top perspective view of a cover panel of a box blank showing a fourth embodiment of my new design, the broken line showing of the adjacent appended components is for illustrative purposes only and forms no part of the claimed design;

FIG. 23 is a top plan view of the fourth embodiment;

FIG. 24 is a bottom plan view of the fourth embodiment; FIG. 25 is a front elevation view of the fourth embodiment; FIG. 26 is a right side elevation view of the fourth embodiment;

FIG. 27 is a left side elevation view of the fourth embodiment; and,

FIG. 28 is a rear elevation view of the fourth embodiment.

My cover panel is characterized by opposing front and rear edges and opposing left and right side edges, with the left

and right side edges being substantially parallel to one another and each forming a substantially right angle to the rear edge, and the front and rear edges being substantially non-parallel to one another and the front edge forming an oblique angle with each of the side edges, one of the oblique angles being an obtuse angle and the other oblique angle being an acute angle.
